UNITED STATES PATENT OFFICE.

FREDERICK HENRY ROYCE, OF WESTWOOD, CROWBOROUGH, ENGLAND.

DESIGN FOR A COMBINED BONNET AND RADIATOR FOR AUTOMOBILE-ENGINES.

45,695.

Specification for Design.

Patented Apr. 28, 1914.

Application filed February 27, 1914. Serial No. 821,587. Term of patent 14 years.

To all whom it may concern:

Be it known that I, FREDERICK HENRY ROYCE, a subject of the King of England, residing at Westwood, Crowborough, Sussex, England, engineer, have invented a new, original, and ornamental Design for a Combined Bonnet and Radiator for Automobile-Engines, of which the following is a specification, reference being had to the accompanying drawing, forming part thereof.

Figure 1 is a front elevation, Fig. 2 is a

side elevation, Fig. 3 is a plan, showing my new design.

I claim:

The ornamental design for a combined bonnet and radiator for automobile engines, as shown.

FREDERICK HENRY ROYCE.
